United States Patent Office.

HIRAM C. PARTRIDGE AND JAMES PRESTON, OF BAINBRIDGE, NEW YORK.

Letters Patent No. 99,227, dated January 25, 1870.

IMPROVEMENT IN POST-AUGERS.

The Schedule referred to in these Letters Patent and making part of the same.

To all whom it may concern:

Be it known that we, HIRAM C. PARTRIDGE and JAMES PRESTON, of Bainbridge, in the county of Chenango, and State of New York, have invented certain new and useful Improvements in Post-Augers; and we do hereby declare that the following is a full, clear, and exact description thereof, reference being had to the accompanying drawings, and to the letters of reference marked thereon, which form a part of this specification.

The nature of our invention consists in the construction of the different parts, forming a post-auger, and in the manner of combining and attaching the same together.

In order to enable others skilled in the art to which our invention appertains, to make and use the same, we will now proceed to describe its construction and operation, referring to the annexed drawings, in which—

Figure 1 is a side elevation of our auger complete; Figure 2 is a plan view of the plate, with the cutter attached;

Figure 3 is a perspective of a washer used to properly connect the different parts; and

Figure 4 is a perspective of the auger-part.

A represents the stem, which at its lower end is pointed and cut with screw-threads, and at its upper end is provided with a handle, B, to turn the auger. On this stem the other parts of the auger are placed in the following manner:

The auger-part C is formed of any suitable metal, with female screw, so that it can be screwed on to the stem A.

It is provided with a steel flange, a, in auger-form, riveted or otherwise secured to it.

Above the auger-part C, and resting upon the same, is the plate D, which is to be of the size the hole is desired. On one side this plate is cut open, the cut extending from the edge to beyond the centre a short distance.

One edge in this cut is bent downward at a suitable angle, and on its upper side is placed the cutter b, which extends along the whole portion thus bent down.

The outer end of the cutter b is provided with a slot running parallel with its outer edge. Through this slot a bolt is passed through the plate D, and held on the under side by a nut, thus securing the cutter, and allowing it to be adjusted at will.

The front or lower edge of the cutter b is rounded as shown by dotted lines in fig. 2.

The stem A passes through the centre of the plate D, the centre being at the inner end of the portion bent down, as above mentioned, and as the cutter b covers this entire portion, the stem A also passes through the inner end of the cutter.

The plate d, although placed horizontal, is still so constructed that the cutter b will form, as it were, a continuation of the auger-flange a.

On top of the plate D, or rather on top of the inner end of the cutter b, and around the stem A, is placed a washer, E, the under side of which is bevelled to correspond with the inline of the cutter, and to present a horizontal surface on its upper side for the nut G, which holds the different parts together at any point on the stem A desired.

Having thus fully described our invention,

What we claim as new, and desire to secure by Letters Patent, is—

1. The manner of holding the plate D upon the stem A, by means of the auger-part C, and nut G screwed on the stem, one below and the other above said plate, substantially as herein set forth.

2. The combination and arrangement of the stem A, handle B, auger-part C, with flange a, plate D, cutter b, washer E, and nut G, all constructed as described, substantially as and for the purposes herein set forth.

In testimony that we claim the foregoing as our own, we affix our signatures, in presence of two witnesses.

HIRAM C. PARTRIDGE.
JAMES PRESTON.
